(57) **CLAIM**

The ornamental design for a lantern, as shown and
described.

DESCRIPTION

FIG. 1 is a top, front perspective view of the lantern of the
present invention showing the new design;

FIG. 2 is a bottom perspective view thereof;

FIG. 3 is a front elevation view thereof;

FIG. 4 is a rear elevation view thereof;

FIG. 5 is a side elevation view thereof;

FIG. 6 is a side elevation view thereof, showing the opposite
side of FIG. 5;

FIG. 7 is a top plan view thereof; and,

FIG. 8 is a bottom plan view thereof.

The broken lines are directed to environment and are for
illustrative purposes only, thus forming no part of the
claimed design.
